DESIGN FOR A CHENILLE ROBE

George H. McLaughlin, New York, N. Y.

Application February 14, 1948, Serial No. 144,498

Term of patent 7 years

(Cl. D3—26)

To all whom it may concern:

Be it known that I, George H. McLaughlin, a citizen of the United States of America, residing in New York city, county of New York, and State of New York, have invented a new, original, and ornamental Design for a Chenille Robe, of which the following is a specification, reference being had to the accompanying drawing, forming part thereof.

Fig. 1 is a front view of a chenille robe, showing my new design.

Fig. 2 is a rear view thereof.

The chenille is shown in discontinued lines.

I claim:

The ornamental design for a chenille robe, substantially as shown and described.

GEORGE H. McLAUGHLIN.
